JOHN H. JUST, OF SYRACUSE, NEW YORK.

VALVE-GRINDER.

1,313,601.

Specification of Letters Patent.

Patented Aug. 19, 1919.

Application filed May 14, 1917. Serial No. 168,397.

To all whom it may concern:

Be it known that I, JOHN H. JUST, a citizen of the United States, residing at Syracuse, in the county of Onondaga and State 5 of New York, have invented certain new and useful Improvements in Valve-Grinders, of which the following is a specification.

This invention relates to improvements in valve grinders, designed particularly for 10 grinding the valves of automobile gas-engines and the like, and has for its object generally to improve, simplify and cheapen devices of the class.

The various features and parts of the invention will be understood from the detailed description which follows, and by reference to the accompanying drawings, in which—

Figure 1 is a view of the complete device in the act of grinding a valve.

Fig. 2 is a central longitudinal section, taken on line 2—2 of Fig. 1.

Fig. 3 is a horizontal section taken on line 3—3 of Fig. 1.

Fig. 4 is a detail view of the bit equipped 25 with spanner-points for grinding spot-hole valves.

In the drawing, 2 represents the body or vertical guide-handle, its upper end comprising a loop 3 for the insertion of a finger for supporting the grinder while in operation. The said loop is also employed for hanging up the device when not in use. The lower end of the body 2 is provided with a substantially triangular loop 4, which is 30 provided with concentric bearings 5 and 6, in which is journaled a round grinding bit 7. The lower end of the bit is preferably flat, like a screw driver, for engaging a slot 8 in the top of certain kinds of valves, as 35 9.

Between the bearings 5 and 6 is disposed a bevel or miter gear 10, which is secured to the bit-stock by a pin 11, and rotates with and drives the bit 7 during the grinding 40 operations. The bottom of the gear 10 nor-

45 mally rests upon the bearing 6, while between the top-end of the gear 10 and the bearing 5 is disposed a cup or race 12 and a series of balls 13. This ball-bearing is employed to reduce the friction of the gear, especially during the grinding operation when there is a certain amount of longitudinal or upward thrust against the bearing 5. A second ball-bearing comprising a race or cup 12' and balls 13', held in place by a 50 collar 14 and a pin 14', may be disposed immediately below the bearings 6, as shown in

Figs. 1 and 2, for further reducing the friction of the parts. The gear 10 and the bit 7 are rotated in opposite directions alternately about one turn during the grinding 60 operation, by an arc-shaped rack 15, which is preferably connected integrally with a handle 16 by arms 15', and these parts are pivoted to the body 2 above the bearing 5 by a pin 17, which pierces the inner end of 65 the handle 16 and also the body 2. The pin 17 has a relatively broad head 17' at one end, while the other end is upset for making the pin rigid with the body, as well as for preventing the loosening or detachment of 70 the parts. The handle 16 is preferably of web construction, for rendering it light, and at the same time giving it adequate strength. The rocking of the handle 16 upwardly and downwardly like a pump handle rotates the 75 gear 10 and the bit 7, and also the valve 9, for effecting the proper grinding of the valve. The arrows in Fig. 1 show the extent of the movement of the handle 16 during the grinding operation. The dotted lines 80 18 (Fig. 1) indicate the closed or folded-up position of the parts, when the device is to be packed for shipment or laid away. The pivot pin 17 is so positioned that the weight of the device above and below said pivot is 85 substantially equal, so that when the operator grasps the handle 16 and holds it at right angles to the body and bit the device is perfectly balanced. By thus balancing the device it is more easily held in true up- 90 right position, which facilitates the true grinding of the valve. The total weight of the device is such that but little extra pressure is required in order to properly grind the valve. A finger or guard 19 is secured 95 to the outer surface of the bearing 6 by a screw 20. The free end of the finger 19 overlaps the rack 15, for preventing its dis-engagement with the teeth of the gear 10.

Fig. 1 shows the bit 7 inserted downwardly in the usual valve casing A and engaging the slot in the valve. Preparatory to the grinding of the valve, the latter is first lifted from its seat 9' in a well-known manner, for releasing the pin (not shown) 100 which usually holds the valve in place, after which a spring 21 is temporarily disposed beneath the valve (see Fig. 1). This spring tends to resiliently lift the valve away from the seat 9' whenever the pressure of the 105 grinder is relaxed and this allows the operator, by slightly shifting the position of the

grinder after several upward and downward strokes of the handle 16, to change the position of the valve relatively to the seat, so as to prevent "ringing" or otherwise unevenly grinding the valve. In this way, the shifting of the valve in the seat may be accomplished without dis-engaging the grinder.

Some valves, as 22, are provided with 10 spot-holes 23 (see Fig. 4) for use in grinding the valves instead of the slots 8, and these valves require means other than the flat-end of the bit 7 for grinding the same. In order to adapt my device for grinding 15 valves of this class, I provide two spanner points 24—24', which are pivoted near the lower end of the bit 7 by a screw or pin 25 which passes through a hole 26. As the 20 spot-holes 23 are spaced differently on different valves, the spanner points may be spread apart or adjusted accordingly. When the points 24—24' are not needed, they may be folded upwardly out of the way as shown by the dotted lines in Fig. 4.

25 In both construction and operation, my valve grinder is extremely simple. It is light in weight, but strong and durable, and owing to its peculiar design, and its direct and positive gearing, as well as the 30 novel and conveniently disposed handle, the device may be used in close quarters, and the valves may be readily, quickly and truly

ground. The equal distribution of the weight of the grinder above and below the handle pivot 17 insures the perfect and 35 true grinding of the valves, and the said work can be accomplished with greater facility and more rapidly than by the use of any other device of the class known to me.

Having thus described my invention, what 40 I claim as new and desire to secure by Letters Patent, is—

A tool of the character described comprising a supporting member having a transverse bearing therein, and a vertical 45 bearing below said transverse bearing, an implement rotatably mounted in said vertical bearing and having secured thereto a pinion, and means for operating the pinion to rotate the tool comprising a toothed segment mounted to swing from the transverse bearing, said segment having an integral handle projecting outwardly therefrom on the same side of the vertical supporting member as the segment and at right angles 50 to a line intersecting the central portion of the segment whereby a movement of the handle on one side of the supporting member permits the entire toothed portion of the segment to coöperate with the pinion to 55 rotate the same.

In testimony whereof I affix my signature.

JOHN H. JUST.
